DESIGN FOR A DRILL PRESS OR SIMILAR ARTICLE

Raymond H. Andresen, Chicago, Ill., assignor to
Peerless Tool & Engineering Co., Chicago, Ill.,
a corporation of Illinois

Application August 2, 1945, Serial No. 121,159

Term of patent 14 years

(Cl. D63—1)

To all whom it may concern:

Be it known that I Raymond H. Andresen, a citizen of the United States and a resident of the city of Chicago, in the county of Cook and State of Illinois, have invented a new, original, and ornamental Design for a Drill Press or Similar Article, of which the following is a specification, reference being had to the accompanying drawings, forming a part thereof.

On the drawings:

Fig. 1 is a perspective view of the drill press, or similar article, taken from the front and one side thereof, showing my new design; and

Fig. 2 is a perspective view thereof taken from the front and other side.

I claim:

The ornamental design for a drill press or similar article, as shown.

RAYMOND H. ANDRESEN.
